UNITED STATES PATENT OFFICE.

JAMES W. TAYLOR AND CHASTAIN H. TAYLOR, OF ASHLAND, VIRGINIA.

IMPROVEMENT IN CHURNS.

Specification forming part of Letters Patent No. **173,828**, dated February 22, 1876; application filed December 31, 1875.

To all whom it may concern:

Be it known that we, JAMES W. TAYLOR and CHASTAIN H. TAYLOR, of Ashland, in the county of Hanover and State of Virginia, have invented certain new and useful Improvements in Churns; and we do hereby declare the following to be a full and exact description of the same, reference being had to the accompanying drawings, forming part of this specification, in which—

Figure 1 represents a perspective view of our improved churn, a portion of the body being broken away to reveal the interior; and Fig. 2 is a central vertical section of the same.

Similar letters of reference in the accompanying drawings denote the same parts.

Our invention relates to that class of churning in which an oscillating dasher is employed to agitate the cream; and has for its object to improve their construction in such manner as to facilitate the churning process and to cheapen the cost of manufacture. To these ends it consists in certain details of construction, which I will now proceed to describe.

In the drawings, A represents the body of the churn, formed, preferably, of wood, and having vertical sides and inclined ends, as shown, and B is the handle or dash-rod, extending through a slot, s, in the cover C, being pivoted on a rod, R, having its bearings in ears E E, formed by a continuation of the sides of the churn. The lower end of the handle, within the body of the churn, is provided with a flat perforated dasher, D, and above the dasher, at right angles thereto, is located a cream-guard, G, consisting of a rectangular piece of wood, secured to the dash-rod, and accurately fitting the sides of the churn, but wide enough to allow considerable play to the dasher.

As the dasher is operated the cream is forced against the ends of the churn but is prevented from flying upward by the guard G, and thus all liability of the cream being thrown out at the top of the churn is prevented, while the churning process is greatly facilitated by thus suddenly confining the cream as it is dashed against the ends of the churn.

The rod R serves as a pivotal point for the handle, and also as a means for keeping the top or cover of the churn tightly in place.

To remove the dasher, the rod R is slipped out and the handle pulled upward, the guard G removing the cover, as will be readily understood.

We are aware that cream-guards have heretofore been arranged on the staff of an oscillating churn, within the body of the churn, immediately beneath the cover, for the purpose of preventing the escape of cream, and we therefore lay no claim to such invention.

By our construction the cream-guard not only prevents escape of cream, but also facilitates the process of churning by affording a surface against which the cream is forced at each oscillation of the dasher.

We claim as our invention—

The cream-guard G, located on the handle B above, and at right angles to, the oscillating dasher D, and acting as a surface against which the cream is dashed, in combination with the churn-body A and dasher D, substantially as described.

JAMES W. TAYLOR.
CHASTAIN H. TAYLOR.
